UNITED STATES PATENT OFFICE.

JOSEPH N. WIGGIN, OF ORANGE, NEW JERSEY.

MACHINE FOR SECURING WINDOW-SHADES TO ROLLERS.

SPECIFICATION forming part of Letters Patent No. 416,881, dated December 10, 1889.

Application filed March 11, 1889. Serial No. 302,839. (No model.)

To all whom it may concern:

Be it known that I, JOSEPH N. WIGGIN, of Orange, in the county of Essex and State of New Jersey, have invented an Improvement 5 in Machines for Securing Window-Shades to Rollers, and the following is declared to be a description of the same.

My invention relates to a machine adapted to secure window-shade fabric to spring-rollers; and the same consists in the combination, 10 with a staple or tack driving machine and a frame for suitably mounting the same, of a traveling carrier adapted to receive the roll of shade fabric, and a sliding rest connected 15 to the traveling carriage and moving therewith, and upon which rest the spring shade-rollers are received and the edge of the shade fabric secured thereto by staples or tacks.

In the drawings, Figure 1 is a cross-section 20 of my improved device and an elevation of the staple-machine, and Fig. 2 is a front elevation of the same in smaller size.

A A' represent the frames of the machine, and B represents the staple-machine. This 25 staple-machine may be of any well-known character—such as is found in the market—or in place thereof a tack-driving machine might be employed.

The machine represented in the drawings 30 is made with double levers *a a'*, a link *b* connecting the adjacent ends of said levers. The hammer *c* is connected to the lever *a*, and the foot-lever rod *d* is connected to the lever *a'*, and this foot-lever rod is operated 35 by an attendant from a treadle or lever on the floor, and *e* represents the row of staples upon a bar, forming part of this machine, which staples are fed forward in the usual manner.

40 C represents the traveling carrier, which is preferably trough-shaped, as shown in cross-section, Fig. 1, and the same is provided with rollers on the under side, resting upon tracks *F*, connected to the frame A'. There are 45 bracket-arms *g*, one at each end of the traveling carrier C, and said arms are curved as shown, and have flattened ends to which the sliding rest *h* is secured, and *i* represents a shade-roller, with a piece of the shade fabric 50 around the same, resting in the notched or

curved face of the sliding rest *h*. There is a plate *k* secured to the edge of the frame A, and the sliding rest *h* bears against one side of this edge plate; and passing through the frame A directly beneath the hammer *c* is an 55 adjusting-screw and its socket *l*, the object of which is to support the rest *h* and shade-roller against the blow in driving the staple and raise or lower the sliding rest *h* so as to bring the roller *i* into its proper relation with 60 the hammer *c*, so that the staples or tacks employed to secure the shade fabric to the roller may be properly driven through the fabric into the roller.

The operation of the device is as follows: 65 An attendant, standing in front of the machine, moves the traveling carrier C and rest *h* to its extreme position at his right hand, and he places within the carrier C a roll of shade fabric cut to length, while alongside of 70 him upon the table or frame A is a number of shade-rollers. He now takes one piece of shade fabric and, raising the same and partially unwinding it, places it around the shade-roller and lays the shade-roller upon 75 the rest *h*, against the grooved face thereof. He now brings the roller *i* to the desired point beneath the hammer *c*, and operates the staple-machine by his foot and the device heretofore named, and drives into the roller one 80 staple at a time, shifting with one hand the carrier C and the rest *h*, and moving the shade-roller and fabric step by step as each staple is driven through such fabric into the roller. As such roller is fastened to a piece 85 of shade fabric the carrier C is drawn back to the starting-point and the operations described repeated.

I claim as my invention—

1. The combination, with a staple-driving 90 machine and supporting-frames, of a traveling carrier for the window-shade fabric, and a slide-rest connected therewith for receiving the window-shade roller, and ways for the same to move upon, substantially as and for 95 the purposes set forth.

2. The combination, with a staple-machine and the frames A A', of the traveling carrier C, for receiving the shade material and the rollers and tracks for the same, the bracket- 100

arms *g*, and the sliding rest *h*, said rest *h* having a grooved or curved face for receiving the shade-roll, substantially as set forth.

3. The combination, with a staple-machine and the frames *A A'*, of the traveling carrier *C*, for the window-shade material, and the rollers and tracks for the same, the bracket-arms *g* and the sliding rest *h*, said rest *h* having a grooved or curved face for the shade-roll, the

edge plate *k* in front of the sliding rest, and the adjusting-screw and socket *l* beneath the slide-rest, substantially as set forth.

Signed by me this 6th day of March, A. D. 1889.

JOSEPH N. WIGGIN.
